UNITED STATES PATENT OFFICE

141,556

DESIGN FOR A MATERIAL LOADING MACHINE

Carmeno A. Onofrio, Gorham, N. H.

Application October 4, 1944, Serial No. 115,606

Term of patent 14 years

(Cl. D41—1)

To all whom it may concern:

Be it known that I, Carmeno A. Onofrio, a citizen of the United States, residing at Gorham, in the county of Coos and State of New Hampshire, have invented a new, original, and ornamental Design for Material Loading Machine, of which the following is a specification, reference being had to the accompanying drawings, forming part thereof.

Fig. 1 is a perspective view, as seen from the front, of a material loading machine showing my new design.

Fig. 2 is a perspective view, as seen from the rear thereof.

When viewed from either side, the appearance of my material loading machine is substantially the same.

I claim:

The ornamental design for a material loading machine, as shown and described.

CARMENO A. ONOFRIO.
